US0D1078807S

(12) **United States Design Patent** (10) **Patent No.:** **US D1,078,807 S**
(45) **Date of Patent:** **** Jun. 10, 2025**

(54) **TANDEM SUB**

(71) Applicant: **XConnect, LLC**, Denver, CO (US)

(72) Inventor: **Shelby L. Sullivan**, Minot, ND (US)

(73) Assignee: **XConnect, LLC**, Denver, CO (US)

(**) Term: **15 Years**

(21) Appl. No.: **29/878,313**

(22) Filed: **Jun. 20, 2023**

Related U.S. Application Data

(60) Division of application No. 29/783,429, filed on May 13, 2021, now Pat. No. Des. 994,736, which is a continuation of application No. 17/110,757, filed on Dec. 3, 2020, now Pat. No. 11,248,452, which is a division of application No. 16/836,193, filed on Mar. 31, 2020, now Pat. No. 10,914,145.

(57) **CLAIM**

The ornamental design for a tandem sub as shown and described.

DESCRIPTION

FIG. 1 is a first perspective view of a tandem sub, showing my new design.

FIG. 2 is second perspective view of the tandem sub of FIG. 1 shown from a different angle, and from an end opposite that of FIG. 9.

FIG. 3 is a top, plan view of the tandem sub of FIGS. 1 and 2.

FIG. 4 is a bottom plan view thereof.

FIG. 5 is a right side elevation view thereof.

FIG. 6 is a left side elevation view thereof.

FIG. 7 is a front plan view of the tandem sub of FIG. 1; and, FIG. 8 is a rear plan view thereof.

(Continued)

The broken lines in the drawings depict portions of the tandem sub that form no part of the claimed design.

1 Claim, 5 Drawing Sheets
